DIRECTIONAL FIRING CASING AND FORMATION GUN

Filed Oct. 9, 1939

UNITED STATES PATENT OFFICE

2,226,073

DIRECTIONAL FIRING CASING AND
FORMATION GUNClarence A. Ricou, Shreveport, La., assignor to
Petroleum Increase Corporation, Carthage,
Tex., a corporation of Texas

Application October 9, 1939, Serial No. 298,724

17 Claims. (Cl. 164—0.5)

My invention relates to oil, gas wells and the like, and includes among its objects and advantages the provision of an improved multidirectional gun for firing projectiles into the formation for the purpose of increasing the production of the well.

In the accompanying drawing:

Figure 1 is an elevational view of a gun in accordance with my invention.

10 Figure 2 is an enlarged elevational view of the gun with certain parts broken away for the sake of clearness.

Figure 3 is a sectional view along the line 3—3 of Figure 2.

15 Figure 4 is a fragmentary sectional detail view of a portion of the perforated nipple which may be associated with the gun, and

Figure 5 is an enlarged sectional detail view 20 illustrating the manner in which the projectiles are mounted in the gun.

In the embodiment selected to illustrate my invention, I make use of a gun body 10 which is circular in cross section and provided with a tapered lower end 12. Body 10 is provided with a 25 threaded bore 14 for threaded connection with a short section of tubing 16 having a threaded neck 18 which may be connected with a perforated nipple 20 through the medium of a coupling 22, see Figure 1.

30 Body 10 is provided with a plurality of longitudinal bores 24, 26, 28 and 30, each of which communicates with the bore 14, as at 32. Bores 24 to 30, inclusive, may be defined as powder trains and the bores respectively communicate with powder chambers 34, 36, 38 and 40.

These chambers have their axes arranged horizontally when the body 10 is positioned vertically in the well preparatory to firing the gun, and the axes of the powder chambers are arranged to fire 40 their respective projectiles 42 in different radial directions through the well casing and into the surrounding formation. All the projectiles 42 are identical in construction, operation, and mounting so that the description of one will apply to all.

45 Referring to Figure 5, the projectile 42 illustrated therein includes a short cylindrical body 44 provided with a lead tapered nose 46 pointing in the direction in which the projectile is fired. Powder chamber 34 includes an enlarged counterbore 48

50 into which the cylindrical body 44 is pressed, with a lead plate 50 pressed into the counterbore and between the rear face 52 of the projectile and the ledge 54.

Body 10 is provided with a relatively large bore 55 56 within which I position a lead washer 58 hav-

ing its central opening 60 fashioned to fit tightly against the tapered nose 46. Adjacent the lead washer 58 I position a copper gasket 62, and against which I position an iron washer or ring 64. Both the gasket 62 and the iron ring 64 have 5 central openings adapted to appropriately engage the tapered nose 46. Internal threads 66 are provided in the bore 56 for the reception of a threaded clamp ring 68 provided with bores 70 for coaction with a suitable wrench.

10 Clamp ring 68 is turned down tightly so as to clamp the lead washer 58, the gasket 62 and the ring 64 tightly on the tapered nose 46 for putting pressure on the lead plate 50, thus providing an effective mount for the projectile in addition to 15 assuring against the entrance of a liquid. Lead plate 50 and the lead ring 64 perform effective sealing functions so as to positively insure against the entrance of moisture. Each powder chamber is filled with a suitable explosive, and the bores or 20 powder trains 24 to 30 inclusive are also filled with the explosive which is also true of the space 32.

Suitable tightening of the clamp ring 68 applies 25 considerable pressure to its respective projectiles 42, which provides an advantageous resistance effective on the projectile when it is fired, thus utilizing the full force of the explosion for firing the projectile through the well casing and into the surrounding formation to a considerable distance.

To fire the explosive, I provide a firing pan assembly 72, see Figure 2. The assembly includes a cylindrical head 74 fitting loosely inside a bore 76 in a sleeve 78 threaded into the bore 80 of a sleeve 82 threaded into the lower portion of the bore 14 and abutting the inner end of the tube 16. Head 35 74 includes a taper 84 fitting against a corresponding taper 86 in the sleeve 78, which sleeve has its bore 88 loosely receiving the cylindrical shank 90 formed as a unit with the head 74.

The head 74 is provided with two pins 92 spaced 40 slightly from primer caps 94 pressed into bores 96 for igniting the explosive in the space 32, which, in turn ignites the explosive in the powder trains 24 to 30 inclusive as well as in their respective powder chamber. Pins 92 are normally slightly 45 spaced from the primer caps 94 and the firing pin assembly is held in its normal position by reason of a shear pin 98.

Means for lowering the gun into a well may 50 comprise tubing 98 connected with the perforated nipple 20 through the medium of a coupling 100. After lowering of the gun, a go-devil is dropped into the tubing 98 for striking the shank 90 of the firing pin assembly. The impact of the go-devil will shear the pin 98 so that the firing pins 92 will 55

be driven into the primer caps 94 for setting off the charge.

The tapered noses 46 of the projectiles facilitate penetration of the well casing as well as the surrounding formation, so that the projectiles will penetrate considerable distances in the formation for shattering or breaking up the formation, as well as to establish direct communication with a new source of oil or the like, thereby increasing 10 the production of the well.

The taper 12 facilitates lowering of the gun, and the body 10 is also tapered at 102 to facilitate raising of the gun inside the well. My invention embodies a plurality of powder chambers, 15 each of which includes an individual powder train operatively related to a common firing mechanism which is actuated through the simple act of dropping a go-devil into the tubing 98.

The individual powder trains provide a construction which more effectively withstands the onrush of fluid into the gun at great depths, thus more effectively insuring against dampening or wetting of the powder after one projectile is fired. The projectiles are fired in successive order because of the variable lengths of the powder trains. Guns lowered to great depths are subjected to enormous pressures. In my invention, the ledges 54 provide effective backing for their respective projectiles 42 so that such pressures merely 30 increase the seal between the powder chambers and the projectiles. Thus fluids are effectively restrained from entering the powder chamber.

Figure 1 illustrates the perforated nipple 20 as being provided with two walls 104, with the 35 perforations located between the two horizontal walls. The walls may comprise metallic plates welded inside the nipple, as illustrated in Figure 4. Thus the walls 104 prevent fluids from passing upwardly of the tubing 98 as well as into the 40 tube 16 which communicates with the firing pin assembly 72. Dropping of the go-devil, the falling go-devil will penetrate both walls in its passage to the firing pin assembly 72. Thus rupturing of the walls, particularly the upper wall permits the well to produce through the tubing 98 through the medium of the perforated nipple 20. A further advantage incident to the perforated nipple 20 lies in the fact that the well can be kept under control at all times and, if necessary, can 50 be washed through the perforated nipple or the well can be filled with fluid or other material passed through the perforated nipple. Another advantage in the perforated nipple lies in the fact that the dry tubing 98 will immediately suck 55 such fluid from the casing or the well when the upper wall 104 is ruptured, thereby placing a vacuum on the surrounding formation, which is desirable from the standpoint of production.

I have found that a ball may be dropped into 60 the tubing 98 after rupturing of the walls 104, with the ball taking a position of rest on the seat 106 so as to function as a closure valve for trapping fluid in the tubing or drill pipe 98. Thus the tube 98 may be elevated, and the trapped 65 liquid will indicate its level in the hole. Accordingly, my invention embodies a construction wherein the gun may be placed, the projectiles fired into the surrounding formation and through the well casing, if necessary, in addition to embodying a structure such that the well may be produced with the gun in the hole, thus effecting a great saving in time and labor.

It will be noted that the powder trains 24 to 30 inclusive, are located close to the outside diameter of the body 10, which arrangement per-

mits the respective powder chambers to be considerably enlarged with respect to length. The two pins 92 provide additional assurance that the gun will be fired when the go-devil is dropped. Occasionally a primer cap might become defective, so that the provision of two caps greatly increases the firing possibilities of the gun. Explosions in the powder chambers 34 to 40, inclusive, will drive the projectiles 42 through the washers 58, the gaskets 62 and the rings 64, with 10 the bores 108 in the clamp ring 68 constituting barrels for the projectiles.

Sleeve 78 coacts with the head 74 to restrain the firing pin assembly from upward movement with respect to any explosion forces effective 15 thereon. The gun may be completely dismantled for reloading purposes so as to be capable of reuse.

Having thus described certain embodiments of my invention in detail, it is, of course, understood 20 that I do not desire to limit the scope thereof to the exact details set forth except insofar as those details may be defined in the appended claims.

What is claimed is:

1. A gun of the type described comprising a 25 body provided with gun bores having their axes arranged in different directions, projectiles aligned with said bores to be fired therethrough, powder chambers behind the projectiles, each powder chamber being provided with a powder 30 train, and a firing means common to all said powder trains.

2. A gun of the type described comprising a body provided with gun bores, projectiles aligned with said bores to be fired therefrom, powder 35 chambers behind the projectiles, each powder chamber being provided with a powder train, and a firing means common to all the powder trains.

3. A gun of the type described comprising a body provided with gun bores having their axes 40 arranged in different directions, projectiles in said bores, explosion chambers behind the projectiles, including an individual bore for each explosion chamber, explosive material in said explosion chambers and said individual bores, and a firing 45 means common to all said individual bores.

4. A gun of the type described comprising a body provided with gun bores having their axes arranged in different directions, projectiles in 50 said bores, explosion chambers behind the projectiles, including an individual bore for each explosion chamber, explosive material in said explosion chambers and said individual bores, a firing means common to all said individual bores, said firing means including an explosion space 55 communicating with said bores and a primer cap, and an impact responsive means for firing said cap.

5. A gun of the type described comprising a body provided with gun bores having their axes 60 arranged in different directions, projectiles in said bores, explosion chambers behind the projectiles, including an individual bore for each explosion chamber, explosive material in said explosion chambers and said individual bores, 65 a firing means common to all said individual bores, said firing means including an explosion space communicating with said trains, and a plurality of primer caps having impact responsive means for firing said caps.

6. A gun of the type described comprising a body provided with gun bores having their axes arranged in different directions, projectiles aligned with said bores to be fired therethrough, powder chambers behind the projectiles, each powder 75

5 chamber being provided with a powder train, a firing means common to all said powder trains, said projectiles extending partly into said bores, and means for holding the projectiles against accidental displacement and coacting with the latter to seal the powder chambers from the entrance of outside moisture.

7. A gun of the type described comprising a body provided with gun bores having their axes 10 arranged in different directions, projectiles aligned with said bores to be fired therethrough, powder chambers behind the projectiles, each powder chamber being provided with a powder train, a firing means common to all said powder trains, said firing means including a primer cap 15 and an impact responsive means for firing the cap, and shear means for normally holding the impact responsive means out of firing engagement with said primer cap.

20 8. A gun of the type described comprising a body provided with gun bores having their axes arranged in different directions, projectiles aligned with said bores to be fired therethrough, powder chambers behind the projectiles, each 25 powder chamber being provided with a powder train, a firing means common to all said powder trains, said firing means including a plurality of primer caps and impact responsive means for 30 firing the caps, and shear means for normally holding the impact responsive mean out of firing engagement with said primer caps.

9. A gun of the type described comprising a body provided with explosive containing chambers having shoulders and projectile receiving bores, 35 projectiles inside the projectile receiving bores, means coacting with said body and the projectiles for holding the latter against said shoulders, said means including bored elements constituting gun bores, an explosive containing bore for each of 40 said explosion chambers, and a firing means common to all said explosive containing bores.

10. A gun of the type described comprising a body provided with explosive containing chambers having shoulders and projectile receiving bores, 45 projectiles inside the projectile receiving bores, means coacting with said body and the projectiles for holding the latter against said shoulders, said means including bored elements constituting gun bores, an explosive containing bore for each of 50 said explosion chambers, a firing means common to all said explosive containing bores, said firing means including a primer cap and an impact responsive element for firing the cap, and shear means for normally holding the impact responsive 55 element out of firing engagement with said primer cap.

11. A gun of the type described comprising a body provided with explosive containing chambers having shoulders and projectile receiving bores, 60 projectiles inside the projectile receiving bores, means coacting with said body and the projectiles for holding the latter against said shoulders, said means including bored elements constituting gun bores, an explosive containing bore 65 for each of said explosion chambers, a firing means common to all said explosive containing bores, said firing means including a plurality of primer caps and impact responsive elements for firing the caps, and shear means for normally holding the impact responsive elements out of 70 firing engagement with said primer caps.

12. A gun of the type described comprising a body provided with explosive containing chambers having shoulders and projectile receiving 75 bores, projectiles inside the projectile receiving

bores, means coacting with said body and the projectiles for holding the latter against said shoulders, said means including bored elements constituting gun bores, an explosive containing bore for each of said explosion chambers, a firing means 5 common to all said explosive containing bores, and a sealing means between the projectiles and their respective shoulders.

13. A gun of the type described comprising a body provided with explosive containing chambers 10 having shoulders and projectile receiving bores, projectiles inside the projectile receiving bores, means coacting with said body and the projectiles for holding the latter against said shoulders, said means including bored elements constituting gun 15 bores, an explosive containing bore for each of said explosion chambers, a firing means common to all said explosive containing bores, and a sealing means incorporated in said first mentioned means. 20

14. A gun of the type described comprising a body provided with explosive containing chambers having shoulders and projectile receiving bores, projectiles inside the projectile receiving bores, means coacting with said body and the projectiles 25 for holding the latter against said shoulders, said means including bored elements constituting gun bores, an explosive containing bore for each of 30 said explosion chambers, a firing means common to all said explosive containing bores, a sealing means between the projectiles and their respective shoulders, and means coacting with said impact responsive element to support the latter against the forces of explosion effective thereon.

15. A gun of the type described comprising a 35 body provided with explosive containing chambers having shoulders and projectile receiving bores, projectiles inside the projectile receiving bores, means coacting with said body and the projectiles for holding the latter against said shoulders, said means including bored elements constituting gun bores, an explosive containing bore for each of said explosion chambers, a firing means common to all said explosive containing bores, a sealing means between the projectiles and their 40 respective shoulders, a perforated nipple connected with said gun, walls in said perforated nipple with the perforations in the latter positioned between said walls, and tubing connected with said perforated nipple, said tubing and said 45 perforated nipple being adapted to guide a gravity propelled mass into impinging relation with said impact responsive element and said walls being adapted to be ruptured by the gravity propelled mass, said perforated nipple constituting a fluid 50 inlet for said tubing on rupturing of said walls. 55

16. A gun of the type described comprising a body provided with explosive containing chambers having shoulders and projectile receiving bores, projectiles inside the projectile receiving 60 bores, means coacting with said body and the projectiles for holding the latter against said shoulders, said means including bored elements constituting gun bores, an explosive containing bore for each of said explosion chambers, a firing 65 means common to all said explosive containing bores, a sealing means between the projectiles and their respective shoulders, a perforated nipple connected with said gun, walls in said perforated nipple with the perforations in the latter positioned 70 between said walls, tubing connected with said perforated nipple, said tubing and said perforated nipple being adapted to guide a gravity propelled mass into impinging relation with said impact responsive element and said walls being adapted 75

to be ruptured by the gravity propelled mass, said perforated nipple constituting a fluid inlet for said tubing on rupturing of said walls, and a seat associated with said nipple above the perforations 5 therein for supporting a valve element dropped thereon for trapping fluid in said tubing above said perforated nipple.

17. A gun of the type described comprising a body provided with powder chambers, said body 10 being provided with a plurality of projectile receiving bores communicating with the powder chambers and having shoulders, projectiles in said projectile bores, sealing means between the projectiles and said shoulders, threaded bores

coaxially aligned with said projectile bores, said projectiles having tapered noses, sealing and retaining means positioned in said threaded bores and engaging the tapered noses of said projectiles, rings having threaded connection with said 5 threaded bores and adapted to press said sealing and retaining means against said tapered noses, said rings having openings constituting barrel bores for the projectiles, with the barrel bores having their axes arranged in different directions 10 one above the other, a powder train for each of said powder chambers, and a firing means common to all said powder trains.

CLARENCE A. RICOU.
